To all whom it may concern:

Be it known that I, Carlos A. Morris, a citizen of the United States, residing at Indianapolis, in the county of Marion and State of Indiana, have invented a new, original, and ornamental Design for a Plaque, of which the following is a specificcation, reference being had to the accompanying drawing, forming part hereof.

In the drawings,

Fig. 1 is a front elevation view of a plaque,
showing my new design.

Fig. 2 is a side elevation thereof.

I claim:

The ornamental design for a plaque, as shown.
CARLOS A. MORRIS.
